(57) **CLAIM**

The ornamental design for an armed tiltrotor aircraft, as shown and described.

DESCRIPTION

FIG. 1 is a top, right front perspective view of an armed tiltrotor aircraft showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a bottom, right front perspective view thereof.

The tiltrotor aircraft depicted by broken lines in the drawings has been shown for the purpose of illustrating environment that forms no part of the claimed design.
